UNITED STATES PATENT OFFICE.

CHARLES J. HALL, OF WILKINSBURG, AND GEORGE C. KENT, OF TURTLE CREEK, PENNSYLVANIA, ASSIGNORS TO WESTINGHOUSE ELECTRIC AND MANUFACTURING COMPANY, A CORPORATION OF PENNSYLVANIA.

DESIGN AND METHOD OF MOLDING THE SAME.

Application filed October 4, 1924. Serial No. 741,620.

Our invention relates to molded articles and has particular reference to a method of producing a print or a design in molded material.

5 The principal object of our invention is, therefore, to produce a design in a molded article which is impregnated with a heat-hardened binder.

Another object of our invention is to provide a method of molding a design in a laminated, impregnated article and of producing a design of uniform color.

Heretofore, designs have been molded in material impregnated with a heat-hardened binder, such as a phenolic condensation product, by placing a sheet of paper upon which the design is printed between sheets of impregnated tissue paper and molding with heat and pressure. This method is satisfactory for most purposes, but the background of the print produced thereby is dark colored and where considerable contrast between the design and the background is desired this method is not satisfactory. When using this method on thin molded articles, the print is apt to break apart in molding. This is especially true where a slight flowing action or readjustment of the body of the material occurs in molding.

Our invention is an improvement on the above process. Instead of disposing the print between sheets of thin absorbent paper, we employ a plurality of sheets of various kinds, which are so treated that we are able to mold a print in the surface of the article without effecting distortion or discoloration thereof.

In the drawing constituting a part hereof and in which like numerals designate like parts;

Figure 1 is an exploded view in perspective of the layers of material comprising the article before molding,

Figure 2 is a plan view of the molded article showing the print thereon, and

Fig. 3 is a side view of the molded article, partially in section.

The body 1 or main portion of the article comprises a plurality of layers of fibrous material such as impregnated paper or duck. Upon the body 1 we place two sheets of impregnated cambric 2 which may be of any desired color but preferably of a light color and over this is placed a sheet of unimpreg-

nated parchmentized paper 3 such as fish paper. The cambric provides a strong backing for the design and is impregnated with a binder such as a phenolic condensation product to such an extent that it provides just the correct amount of binder to properly consolidate the fish paper. The fish paper being parchmentized prevents an excess of binder from the backing sheets 1 or from the cambric 2 from flowing therethrough and discoloring the outer layers of the paper when subjected to heat and pressure. The design which is printed on unimpregnated calendered paper 4 is placed over the fish paper 3 and a sheet of impregnated paper 5, such as jap paper or tissue paper is placed on the outer surface. The amount of binder in the jap paper is just sufficient to consolidate sheets 3, 4 and 5 when subjected to heat and pressure and provides a clear transparent surface without causing any discoloration or clouding of the print 4.

Our invention provides a molded article comprising impregnated and unimpregnated fibrous material. When the article is consolidated with heat and pressure, it provides a structure, which may be used as a name plate or a design as molded. The design or print may be molded in the surface of a thin plate and attached to another article with screws or other suitable means; or the design may be molded in the surface of a molded article comprising non-laminated or impregnated sheets of laminated material.

Although we have described a specific embodiment of our invention we do not wish to be limited thereto as other modifications of our invention will suggest themselves to those skilled in the art without departing from the spirit of our invention. For example we may substitute other forms of impervious paper for the fish paper of layer 3.

We claim as our invention:

1. The method of molding designs which comprises superimposing impregnated fabric on a body portion of impregnated molding material, placing a sheet of parchmentized paper thereon, disposing a print between said paper and a sheet of transparent impregnated paper and curing with heat and pressure.

2. The method of molding designs which comprises superimposing impregnated cam-

bric on the body portion of impregnated molding material, placing a sheet of parchmentized paper thereon, disposing a print between said paper and a sheet of transparent impregnated paper and curing with heat and pressure.

3. The method of molding designs in the body of impregnated material which comprises placing an impregnated fabric of light color on said body, placing thereon a design printed on unimpregnated calendered paper and disposed between a sheet of parchmentized paper and a sheet of transparent impregnated paper and curing with heat and pressure.

4. The method of molding designs in a body of impregnated material which comprises placing an impregnated fabric of light color on said body, placing thereon a design printed on unimpregnated calendered paper and disposed between a sheet of unimpregnated parchmentized paper and a sheet of transparent impregnated paper and curing with heat and pressure.

5. The method of molding designs in a body of impregnated material which comprises placing an impregnated fabric of light color on said body, placing thereon a design printed on unimpregnated calendered paper and disposed between a sheet of parchmentized paper and a sheet of thin transparent impregnated paper and curing with heat and pressure.

6. A method of molding which comprises

providing a body of moldable material, placing impervious unimpregnated material thereon, disposing an ornamented design thereon, covering the same with thin impregnated material, and consolidating the assembly.

7. A method of molding which comprises providing a backing of moldable material of light color, placing impervious unimpregnated material thereon, disposing an ornamented design thereon, covering the same with thin impregnated material, and consolidating the assembly.

8. A molded design comprising an ornamented design, a backing therefor, a layer of impervious material interposed therebetween and a transparent covering layer on said design.

9. A molded design comprising an ornamented design, a backing of material of light color therefor, a layer of impervious material interposed therebetween and a transparent covering layer on said design.

10. A molded design comprising an ornamented design, a backing of fabric of light color therefor, a layer of impervious material interposed therebetween and a transparent covering layer on said design.

In testimony whereof, we have hereunto subscribed our names this first day of October, 1924.

CHARLES J. HALL.
GEORGE C. KENT.
